(57) **CLAIM**

The ornamental design for a cover for electronics of motorized hand truck, as shown and described.

DESCRIPTION

FIG. 1 is a perspective view showing the front, top and right side view of a cover for electronics of a motorized hand truck showing my new design.

FIG. 2 is a perspective view showing the rear, top and right side thereof.

FIG. 3 is a front view thereof.

FIG. 4 is a top view thereof.

FIG. 5 is a right side view thereof.

FIG. 6 is a left side view thereof.

FIG. 7 is a rear view thereof; and,

FIG. 8 is a bottom view thereof.

The broken line showing of a cart is included for the purpose of illustrating portions of the 'article' and forms no part of the claimed design.
